US00D957648S

(12) **United States Design Patent** (10) **Patent No.:** **US D957,648 S**
Al-Ali (45) **Date of Patent:** **** Jul. 12, 2022**

(54) **DONGLE**

(71) Applicant: **MASIMO CORPORATION**, Irvine, CA (US)

(72) Inventor: **Ammar Al-Ali**, San Juan Capistrano, CA (US)

(73) Assignee: **Masimo Corporation**, Irvine, CA (US)

(**) Term: **15 Years**

(21) Appl. No.: **29/666,519**

(22) Filed: **Oct. 12, 2018**

(51) LOC (13) Cl. **24-01**

(52) U.S. Cl.

USPC **D24/186**; D14/480.1; D14/433; D14/358

(58) **Field of Classification Search**

USPC ..... D24/164–169, 186, 187, 107, 216; D10/70, 75, 78, 98, 103; D14/344, D14/138 R, 138 AA, 155, 240, 242, 358, D14/433, 435.1, 436, 480.1, 480.3, 480.4, D14/480.6, 480.7, 484.1

(57) **CLAIM**

The ornamental design for a dongle, as shown and described.

DESCRIPTION

FIG. 1 is a front and side perspective view of a dongle embodying our new design;

FIG. 2 is a back and side perspective view thereof;

FIG. 3 is a back view thereof;

FIG. 4 is a front view thereof;

FIG. 5 is a left side view thereof, and the right side view is a mirror image of the left side view;

FIG. 6 is a bottom view thereof;

FIG. 7 is a top view thereof;

FIG. 8 is a front and side perspective view thereof, with the design shown in its environment;

FIG. 9 is a right side view thereof; and,

FIG. 10 is a back and side perspective view thereof, with the design shown in its alternative environment.

The broken lines, where shown, are used to illustrate portions of the dongle or environmental subject matter that form no part of the claimed design.

1 Claim, 9 Drawing Sheets
